UNITED STATES PATENT OFFICE.

FREDERICK W. PARSONS, OF ELMIRA, NEW YORK, AND FRANCIS A. JIMERSON, OF ATHENS, PENNSYLVANIA, ASSIGNORS TO INGERSOLL-RAND COMPANY, OF JERSEY CITY, NEW JERSEY, A CORPORATION OF NEW JERSEY.

BUILT-UP CRANK SHAFT.

Application filed June 1, 1922. Serial No. 565,067.

To all whom it may concern:

Be it known that we, FREDERICK W. PARSONS, a citizen of the United States, and a resident of Elmira, county of Chemung, and State of New York, and FRANCIS A. JIMERSON, a citizen of the United States, and a resident of Athens, county of Bradford, State of Pennsylvania, have invented a certain Built-Up Crank Shaft, of which the following is a specification accompanied by drawings.

This invention relates to built up crank shafts for fluid actuated multi-cylinder engines, and the objects of the invention are to simplify and strengthen such crank shafts, obtain better balance and more perfect alignment of bearings, and permit the use in the engine of solid end connecting rods, rather than multiple piece connecting rods or rods of the toggle type. Another object of the invention is to enable the parts to be readily assembled and disassembled.

To these ends, the invention is illustrated in one of its preferred forms in the accompanying drawings, in which—

Figure 1 is a side elevation partly in longitudinal section of an assembled crank shaft,

Figure 2 is an end view of the crank shaft,

Figure 3 is a transverse sectional view on the line 3—3 of Figure 1, looking in the direction of the arrows, and illustrating the method of disassembling the parts,

Figure 4 is a view similar to Figure 3, with the central bolt through the center web of the crank shaft in position,

Figure 5 is a side elevation of one end web and crank pin,

Figure 6 is a transverse sectional view taken through the center web, and

Figure 7 is a side elevation of the opposite end web and crank pin.

Referring to the drawings, the crank shaft comprises the center web A having transverse apertures B at each end for the reception of the crank pins C, which are adapted to be located and aligned in the center web in any suitable manner, preferably by means

of the locking pins D passing through the center web and the crank pins.

The shaft ends E and F, are provided with end webs G and H carrying the crank pins C, which are formed integral with said end webs G and H. The end webs G and H are also preferably provided with counterweights J and K. The shaft ends E and F also carry the main bearings L and O which may be in the form of ball bearings, and the driving pinion P is shown keyed to the shaft end E.

In accordance with my construction, the center web A is formed with a central longitudinal slot Q in the body portion of the web connecting the transverse apertures B, and a bolt R having the nut S passes centrally through the body portion of the web A transversely to the axis of the crank shaft for drawing the two portions of the web body tightly together when the parts are assembled, thus rigidly gripping the crank pins. The bolt R as shown, is preferably in screw threaded engagement with the portion V of the center web. In order to quickly disassemble the parts of the crank shaft, the bolt R is removed and the bearing plate T is inserted in the slot Q. A screw U is screwed into the threaded portion V of the center web and bears against the bearing plate T so that the two portions of the body of the web are forced apart, thus loosening the crank pin C which may be readily removed.

I claim:

1. A built up crank shaft for multi-cylinder engines, comprising a center web having transverse apertures at each end, shaft ends having end webs carrying crank pins integral therewith and adapted to be inserted in the transverse apertures in the center web, and locating means for aligning the shaft ends and means for locking the web body firmly to the crank pins.

2. A built up crank shaft for multi-cylinder engines, comprising a center web having transverse apertures at each end, and a central longitudinal slot in the body portion of the web connecting said apertures, shaft

ends having end webs carrying crank pins integral therewith and adapted to be inserted in the transverse apertures in the center web, locating means for aligning the shaft ends, and a bolt passing through the body portion of the web transversely to the axis of the crank shaft for drawing the two

portions of the web body together, and locking the web body firmly to the crank pins.

In testimony whereof we have signed this 10 specification.

FREDERICK W. PARSONS.
FRANCIS A. JIMERSON.
